Application June 17, 1931, Serial No. 544,959

24 Claims. (Cl. 178—6.8)

My invention relates to improvements in methods and apparatus for communication by television and, more particularly, to improved methods and apparatus for synchronizing operations 5 at the transmitting and receiving stations.

One of the objects of my invention is to provide an improved system for communication by television having advantages over those proposed heretofore as regards the method of and means 10 for synchronizing scanning operations at the transmitting and receiving stations.

Another object is to obtain, in a system of the character referred to, a saw-tooth wave of the best form for scanning, and this with less power 15 than has been the case in the various systems proposed heretofore.

Another object is to provide an improved system of the character referred to by which a picture of increased fidelity is produced.

Other objects and advantages will hereinafter appear.

In accordance with my invention, in a system for communication by television wherein a disc or other equivalent rotating means is used for scanning, and wherein horizontal synchronizing and framing frequencies are required for synchronizing operations at the transmitting and receiving station, the scanning means is utilized to develop impulses at the horizontal synchronizing frequency and certain of these impulses, occurring 20 at the framing frequency, have a shape differing from that of the others, the different shape being due to these certain impulses having a greater amplitude and/or a greater duration.

Further, in accordance with my invention, the aforementioned rotating means is utilized to develop the horizontal synchronizing frequency at an edge of the picture frame, more specifically, one of the vertical edges, and to develop the framing frequency at another edge of the picture frame, more specifically, one of the horizontal edges.

Further, in accordance with my invention, means including a single photoelectric cell are utilized to supply both the horizontal synchronizing and framing frequencies, the rotating means forming part of such means.

Further, in accordance with my invention, for the purpose of obtaining from a given voltage wave a similar current wave in any given electrical circuit, the voltage wave is utilized to force a similar current wave through a second electrical circuit whose frequency-impedance characteristic is similar to that of the first circuit, 50 the back E. M. F. voltage across the second cir-

cuit is amplified, and such amplified voltage is applied to the first circuit to cause the required current wave to pass through the same.

Further, in accordance with my invention, a saw-tooth voltage wave is developed by utilizing 5 a thermionic tube to discharge a condenser which is continuously charged from a relatively high potential source, the tube being biased far below the cut-off point, and a dynatron oscillator is used to develop sharp voltage peaks, the tips only 10 of which are effective to drive the tube.

Further, in accordance with my invention, a saw-tooth voltage wave is developed by using a circuit including a discharge tube and a voltage amplifier tube, and a D. C. amplifier connection 15 is used between these tubes for impressing, on the grid of the amplifier tube, the voltage wave across the plate circuit of the discharge tube.

My invention resides in the methods of operation and in the circuits, arrangements, and constructions of the character hereinafter described.

For the purpose of illustrating my invention, several embodiments thereof are shown in the drawings, wherein—

Figure 1 is a diagrammatic view of a television 25 transmitting station embodying my invention;

Fig. 2 is a side elevational view of the scanning disc used at the transmitting station, looking toward the left in Fig. 1;

Figs. 3 and 4 are enlarged fragmentary views 30 looking toward the left in Fig. 1;

Figs. 16 and 17 are graphical illustrations of the operating action in Fig. 15;

Fig. 18 is a diagrammatic view of a proposed modification of the circuits in Figs. 9 and 15; and

Figs. 19, 20, and 21 are graphical illustrations of the principle of operation in Fig. 22.

The transmitting station shown in Fig. 1 is of the general type disclosed in the copending application of Harry H. Bates, Serial No. 445,315 filed April 18, 1930, and assigned to the Westinghouse Electric and Manufacturing Company.

A scanning disc 10 is driven by a suitable constant speed motor 11 at 1200 R. P. M., for example, and is interposed in the usual manner between a suitable light source 12 and a lens or lens system 13. A mask 14 is supported between the light source and disc 10.

The disc 10 is provided, for example, with sixty scanning holes A₁—A₆₀, spirally arranged in the usual manner. The holes A₆₀, A₁, and A₂ are plugged, as indicated. The reason for this will be hereinafter explained.

Light reflected from an object 15 excites a photoelectric cell 16, or a bank of such cells, to develop picture signals which are amplified by 15 an amplifier 17 and applied to the input line 18 of a second amplifier 19. The second amplifier 19 is connected, as shown, to a suitable modulator 20 which controls a radio transmitter 21.

For the purpose of synchronizing operations at 20 the transmitting and receiving stations, electrical synchronizing impulses, at the horizontal synchronizing and framing frequencies, are required. The present improved methods and means for developing these two frequencies will now be explained, with reference more particularly to Figs. 2 to 6.

The disc 10 is provided at the outer edge thereof with concentrically arranged holes a₁ to a₆₀, through which light from a light source 22 passes to a photoelectric cell 23, as shown in Fig. 1. A screen 24, provided with an aperture 25 substantially equal in width to that of the synchronizing holes, is interposed between the disc 10 and the light source 22. A lens 26 may be employed to focus the light on the photoelectric cell.

There being sixty synchronizing holes, the photoelectric cell 23 develops electrical impulses at a horizontal synchronizing frequency of 1200 40 cycles per second. The impulses or signals at this frequency are amplified by a suitable amplifier 27 and are supplied directly to the input line 18 of the amplifier 19, in parallel with the amplified picture signals.

The width of the opening 28 in the mask 14 is made less than the circumferential distance between adjacent scanning holes, as shown in Fig. 3, to provide for periods during which no picture signals are transmitted. The adjustment of the 50 screen 24 is such that during these periods the synchronizing holes a₁ to a₆₀ move across the aperture 25.

Three picture lines are omitted by plugging holes A₆₀, A₁, and A₂. The synchronizing hole a₁ is equal in width to but is longer than the others, and moves across aperture 25 as the plugged hole A₁ moves back of the righthand edge of opening 28.

The above construction and arrangement provides for development, at a vertical edge of the field of view, of impulses at the horizontal synchronizing frequency, and for development, at a horizontal edge of the field of view, of impulses at the framing frequency. The duration of the 65 framing impulses is equal to that of the other synchronizing impulses because the width of hole a₁ is equal to the width of the other synchronizing holes. The amplitude of the framing impulses, however, is substantially greater because 70 of the greater length of hole a₁.

From the foregoing, it will be seen that although the synchronizing signals are transmitted in the same channel with the picture signals, the former are developed only during periods when 75 the picture signals are cut off, and for this reason

interfere in no way with the picture fidelity at the receiving station.

When it is desired that the framing impulses be of greater duration as well as be greater in amplitude than the other synchronizing impulses, the hole a₁ in Figs. 2 and 4 is given the shape shown in Fig. 5. That is, the size and shape of the framing hole in Fig. 5 is such that the same not only moves across aperture 25 for a longer period, but during such movement admits more light to the photoelectric cell 23 than the other synchronizing holes.

If the requirements are such that the framing impulses be of the same amplitude but of greater duration than the other synchronizing impulses, 15 in order to distinguish the former from the latter at the receiving station, the hole a₁ in Figs. 2 and 4 is given the shape shown in Fig. 6. That is, the size and shape of the framing hole in Fig. 6 is such that the same moves across aperture 25 20 for a longer period, and during such movement admits the same maximum amount of light to cell 23 as the other synchronizing holes.

The number of stages in amplifiers 17 and 27 is such that the output voltage of amplifier 27 25 is 180 degrees out of phase with that of amplifier 17, an increase in light intensity on the picture cell 16 causing a corresponding increase, in the positive sense, in the output voltage of amplifier 17. Therefore, when the synchronizing 30 cell 23 is exposed to the light from source 22, there is a sharp increase in the negative direction, in the output voltage of amplifier 27.

The synchronizing holes a₁ to a₆₀ may be disposed on the inside of the scanning holes, if 35 desired. It is also contemplated, if and when found desirable, to employ a separate disc for synchronizing purposes. In such case, the synchronizing disc would be driven by motor 11, and provided with synchronizing holes arranged and 40 formed as described above.

For convenience of explanation, the scanning holes A₆₀, A₁, and A₂ have been described as such, and it has been stated that these holes are plugged to omit several picture lines. In actual 45 practice, however, the disc is not apertured at all at these spots.

While the scanning disc has been described as providing for 60 picture lines, it will be understood that the design may be varied to provide 50 for more or less lines, as might be found desirable for particular conditions. Furthermore, the scanning disc may be replaced by a scanning cylinder or other equivalent rotating means of well known construction. If a scanning cylinder is 55 used, the same may be provided with the synchronizing holes, or a separate cylinder may be employed for the synchronizing action, as explained above in connection with the disc construction.

The amplifiers 17, 19, and 20, and the usual power amplifier forming part of the radio transmitter, are of any well known construction having the following desirable characteristics:

(1) Amplification substantially constant at all 65 required frequencies.

(2) The time-lag in the amplifiers to be either zero or substantially constant at all required frequencies.

(3) The amplification to be substantially constant at all required signal amplitudes. The modulator 20 to give practically constant modulating power over the required frequency range.

Coming now to consideration of the construction and principle of operation of the receiving 75

station, the same is shown diagrammatically in Fig. 7, and includes a cathode ray tube 35 of the general type disclosed in the copending applications of Vladimir K. Zworykin bearing Serial Nos. 407,652 and 504,559, and filing dates of November 16, 1929 and December 24, 1930, respectively.

The transmitted picture signals and the horizontal synchronizing and framing signals are received by a suitable radio receiver 36. After appropriate amplification, these signals all appear across a plurality of resistors 37, 38, and 39, each connected directly across the output line 36a of the receiver. The picture signals are taken from resistance 37 by an adjustable contact 40 and applied to the control grid 41 of the tube.

The grid 41 is biased negatively with respect to the cathode 42, as indicated, the negative bias being variable by the adjustable contact 43 to suit particular requirements.

The cathode 42 is indirectly heated by a suitable filament 42a supplied with alternating current at 2.5 volts.

The contact 44 is adjusted to apply to the first anode 45 a positive potential of substantially one thousand volts.

The second anode is maintained at a positive potential of substantially five thousand volts, and comprises a silver coating 46 on the interior 30 surface of the tube and a coating or screen 47 of fluorescent material on the end wall, the screen being electrically conductive and in electrical contact at its edge portion with the adjacent edge of the silver coating.

The electrostatic field developed by the silver coating, at the positive potential of five thousand volts, is effective to focus the cathode ray 48 to a well defined spot on screen 47. This high potential on the silver coating and screen operates 40 to step up the velocity of the electrons to a relatively high value, after deflection of the ray, so that the desired degree of fluorescence of the screen is obtained as the electrons strike it.

The particular values of potential given have 45 been found to be satisfactory for successful operation, but may be varied over a wide range, as required to suit particular conditions.

For the purpose of causing the ray 48 to scan the screen 47, a 1200 cycle saw-tooth current 50 wave is caused to pass through the horizontal deflecting coils 49, and a 20 cycle saw-tooth current wave is caused to pass through the vertical deflecting coils 50.

The reference numeral 51 designates a system 55 for supplying the 1200 cycle saw-tooth current wave for the coils 49. The operation of this system is controlled by and maintained in synchronism with the scanning action at the transmitting station by the received horizontal synchronizing impulses taken from resistor 39 by the adjustable contact 52.

The reference numeral 53 designates a system 60 for supplying the 20 cycle saw-tooth current wave for coils 50. The operation of this system is controlled by and maintained in synchronism 65 with the scanning action at the transmitting station by the received framing impulses taken from the resistor 38 by the adjustable contact 54.

As will hereinafter more fully appear, the adjustment of the system 51 is such that it is responsive only to the received horizontal synchronizing impulses or signals, taken off at the contact 52, which are of substantially greater amplitude than the peak picture signals taken off 70 at the contact 40, the amplitude of the peak

picture signals being well below the value necessary to drive or control this system. The synchronization of the system 51 with the scanning action at the transmitting station is, therefore, unaffected by and entirely independent of the 5 picture signals, although both the synchronizing and picture signals are taken directly from the output line 36a of the radio receiver. The purpose of making the amplitude of the transmitted synchronizing impulses substantially greater 10 than that of the peak picture signals transmitted, in this case about twice as great, will now be apparent. The advantage of this is that no filter is required at the receiving station to separate the synchronizing and picture signals. 15

Also, the adjustment of the system 53 is such that the same is responsive only to the received framing impulses, taken off at contact 54, which are of substantially greater amplitude than the peak picture and horizontal synchronizing signals, the amplitude of the latter being well below the value necessary to drive or control this system. The synchronization of the system 53 with the framing period at the transmitting station is, therefore, unaffected by and entirely independent 20 of the picture and horizontal synchronizing signals, although the framing, horizontal synchronizing and picture signals are all taken directly from the output line 36a of the receiver 36. The purpose of making the amplitude of the transmitted framing impulses substantially greater 25 than that of the peak picture signals and the horizontal synchronizing impulses, in this case about three times as great as the amplitude of the peak picture signals, will now be apparent. The 30 advantage of this is that no filter is required at the receiving station to separate the signals for framing from the picture and the horizontal synchronizing signals.

The operation at the receiving station is as 40 follows: Picture signals are applied to the grid 41 to vary the intensity of the ray 48 in accordance with conditions of light and shade of the object 15. At the completion of each picture-line, the picture signals cease due to the masking 45 action at the transmitting station, and a horizontal synchronizing impulse occurs in each of the resistors 37, 38, and 39. This impulse is effective to synchronize the system 51, but has no effect on the system 53 on account of the adjustment, 50 as explained.

The horizontal synchronizing and framing impulses swing grid 41 in the negative direction due to the fact that the amplifiers 17 and 27 at the transmitting station are 180 degrees out of phase, 55 as explained. In other words, the picture signals increase in value from a zero base line in one direction, and the synchronizing impulses are measured in amplitude from the same zero base line, but in the opposite direction. That is, in 60 my improved system, there is what might conveniently be termed polarity separation between the picture signals and the synchronizing impulses. The advantage of this action is that the horizontal synchronizing and framing impulses cause 65 narrow dark borders to appear along the right-hand vertical and the upper horizontal edges of the received picture, rather than bright borders of considerably greater light intensity than the picture and which would contrast unpleasantly 70 therewith. Another advantage of this action is that the load on the transmitter is substantially lower than would otherwise be the case.

During the periods between picture frames, the framing impulses occur across each of the resist- 75

ors 37, 38, and 39, and are effective not only to synchronize system 51, but also system 53 on account of their relatively great amplitude. No picture signals occur across resistors 37, 38, and 5 39 during these intervening periods due to the fact that the scanning holes A₀, A₁, and A₂ are plugged.

Adjustment of the contact 43 operates to control the background brilliancy of the picture, 10 while the amplitude of the picture signals applied to grid 41 is varied by adjusting contact 40.

The various circuits which I propose using for the systems 51 and 53 will now be described.

In Fig. 8 is shown a circuit proposed for system 15 51. For the purpose of obtaining a saw-tooth voltage wave, a glow tube 55 operates to discharge a condenser 56 which is continuously charged, through a high resistance 57, from a D. C. potential source, the potential in this case being 500 20 volts. The adjustment of resistor 57 and the capacity of condenser 56, for the charging potential of 500 volts, are such that the natural period of charge and discharge of the condenser is slightly lower than $\frac{1}{1200}$ second. Each received 25 synchronizing impulse, however, taken off at contact 52 and applied to the glow tube through a suitable step-down transformer 58, is effective to bring the tube up to the discharge point from a point just below the same. In this way, the 30 charge taken by the condenser is fixed, and the cycles of charge and discharge maintained at 1200 a second, in synchronism with the scanning action at the transmitting station.

The condensers 59 and 60 form a capacity 35 potentiometer, reducing the voltage to obtain the required "swing" for the grid circuit of the following screen grid tube 61.

The 5 megohm resistor shown supplies a bias to tube 61.

40 The condensers 59 and 60 are charged and discharged in the same manner as condenser 56, the highest voltage appearing across the smallest condenser.

A circuit 62, including an inductor 63 and an 45 adjustable resistor 64, is connected as shown in the plate circuit of tube 61.

The back E. M. F. voltage across the circuit 62 is applied to the grid of a power tube 65 which 50 operates as a voltage amplifier.

50 The circuit 62 simulates the circuit comprising coils 49, that is, the resistance 64 is adjusted so that the circuit 62 has the same ratio of inductance to resistance as the coils 49. The impedance of coils 49 is greater than that of tube 65, while 55 the impedance of the circuit 62 is less than that of tube 61.

The operation of the circuit in Fig. 8 is as follows: A saw-tooth voltage wave 66, of the same 60 shape as the saw-tooth current wave 67 required through coils 49, is generated by glow tube 55 and the associated condenser 56. This voltage wave is applied to, or drives the tube 61 which forces a corresponding saw-tooth current wave 68 through the circuit 62. The back E. M. F. voltage 65 wave 69 across circuit 62 is of the exact shape required to pass a saw-tooth current wave, similar to wave 68, through any circuit having the same frequency-impedance characteristic as the circuit 62. Therefore, when the voltage wave 69 is applied to the grid of the voltage amplifier tube 65 and amplified, thereby to obtain the similarly-shaped but amplified voltage wave 70 in the plate 70 circuit of tube 65, the required saw-tooth current wave 67 will pass through coils 49. This circuit 75

and method of operation permits of the output or power tube 65 working at maximum efficiency.

In order that the power tube 65 can operate to maintain the voltage wave 70 across coils 49 the same as the voltage wave 69 applied to its grid, 5 it should have zero internal resistance. The internal resistance of this tube acts very nearly the same as if it were in series with coils 49. This is compensated for by making the ratio of inductance to resistance in the plate circuit of tube 10 61 a little less than this ratio in coils 49.

The values of resistance, inductance, capacity, and voltage given in Fig. 8 have been found to be satisfactory for the purpose of obtaining a practically perfect saw-tooth deflection of the 15 ray 48.

While the circuit and method of operation just described has been shown embodied in a television system to effect saw-tooth deflection of the cathode ray by electromagnetic coils, this part of my 20 invention is of much broader adaptation, and would have utility in other environments. For example, in sound reproduction, the frequency-impedance characteristic of output transformers and loudspeakers could be compensated for 25 by connecting a circuit of identical frequency-impedance characteristic in the plate circuit of a tube which would correspond to the tube 61 in Fig. 8. In such a system, the primary of the transformer, or the actuating coil or coils of the 30 loudspeaker, as the case might be, would be connected in the plate circuit of a voltage amplifier tube corresponding to the tube 65 in Fig. 8. In other words, the broadest aspect of this part of my invention is to obtain, from a given voltage 35 wave of any definite, indefinite or varying shape, a current wave of the same shape through any electrical circuit or network regardless of the frequency-impedance characteristic of the latter. In accordance with my invention, this is accomplished by applying the given voltage wave to the 40 grid of a tube, such as screen grid tube 61 in Fig. 8, to force a current wave of the same shape as the given voltage wave through a circuit connected in the plate circuit of this tube and having substantially the same frequency-impedance characteristic as a second circuit through which it is 45 desired to pass the current wave. The back E. M. F. voltage across the first circuit is then applied to the grid of a voltage amplifier tube. 50 The amplified voltage wave in the plate circuit of the amplifier tube is then utilized to cause a current wave of the same shape as the original voltage wave to pass through the second circuit. In Fig. 8 the second circuit here referred to is 55 constituted by the coils 49.

From the foregoing description of the circuit in Fig. 8, it will be apparent that the perfection of saw-tooth deflection of the cathode ray 48 by coils 49 is dependent upon the perfection of the 60 original saw-tooth voltage wave 66.

In the circuit shown in Fig. 9, the various parts which are the same as or correspond to equivalent parts in Fig. 8 are designated by the same respective reference numerals as the latter. From 65 this it will be seen that in Fig. 9, the circuit from condenser 56 on through to the deflecting coils 49 is the same as this portion of the circuit in Fig. 8. In Fig. 9, however, the means for generating the original saw-tooth voltage wave is 70 different, and includes an additional condenser 71 which is continuously charged from the 500 volt supply through a high resistance 72. The voltage on the condenser 71 increases until the breakdown voltage of a suitable glow tube 73 is 75

reached. The breakdown periods of the tube 73 are controlled by and occur with the received synchronizing impulses taken from the resistor 39 by the contact 52.

5 When the tube 73 breaks down to discharge the condenser 71, a heavy current is sent through the inductor 74. The steep wave front of the current through the inductor 74 causes a high voltage to be suddenly developed across the same, 10 the voltage wave having substantially the shape shown in Fig. 10.

The discharge tube 55a for the condenser 56 is shown as a screen grid tube, and corresponds to the glow tube 55 for discharging this condenser in Fig. 8. The discharge tube 55a is biased far below cut-off to a point whereat it will require, for the purpose of "swinging" the grid of this tube, a positive voltage at least as high as that designated by the dash line 75 in 20 Fig. 10.

The condenser 56 continues to acquire a charge until it is discharged by the discharge tube 55a. The adjustment of the resistor 57, the capacity of condenser 56, and the charging voltage are 25 such that, within the range of the condenser-charging curve used, the voltage across the condenser increases substantially linearly with respect to time. When one of the steep impulses 76 swings the grid of tube 55a positive, the latter 30 instantly becomes effective to discharge condenser 56, and continues to do so for the period of time during which the voltage wave in Fig. 10 is above line 75, after which the condenser again starts to acquire a charge substantially linearly 35 with respect to time. A saw-tooth voltage wave 78 is thereby obtained across the condenser 56, as is more clearly shown in Fig. 11 wherein the effective tip portions 77 of the voltage impulses 76 are shown on the time axis at the discharge 40 periods.

From the foregoing, it will be seen that the length of return time of the saw-tooth wave 78 is determined by the time period t , since the condenser 56 is, at all other times, charging. The return time of the voltage wave 78 is, therefore, 45 very substantially shorter than could possibly be the case for the saw-tooth voltage wave 66 generated in Fig. 8 by the glow tube 55 and the associated condenser. It will be seen further that, in Fig. 9, adjustment of the condenser 56 and the resistor 57, so that the condenser charges on the most advantageous portion of the charge 50 curve, has no effect upon the speed or frequency of the saw-tooth wave developed.

55 The operation of the circuit in Fig. 9 from the condenser 56 to the deflecting coils 49 is the same as that in Fig. 8.

As in Fig. 8, the values of resistance, inductance, and capacity designated in Fig. 9 have been 60 found to be satisfactory for successful operation.

Any voltage wave having a sharp peak may be used to drive tube 55a.

A grid glow tube, a thyratton, or any other suitable discharge device may be substituted for the glow tube 73. For example, Fig. 12 shows the manner of connecting a grid glow tube 73a in the circuit shown in Fig. 9 to replace and serve the same purpose as the glow tube 73.

As shown in Fig. 13, a resistance 74a may be 70 used instead of the inductor 74 in Fig. 9, in which case the shape of the voltage wave would be substantially as shown in Fig. 14. In Fig. 14, the top portions 79 of the impulses serve the same purpose as the top portions 77 of the impulses in Fig. 10.

For the purpose of developing voltage peaks to drive the tube 55a in Fig. 9, it is proposed in some cases to substitute, for the glow tube 73 and its associated parts, a dynatron oscillator 80, as shown in Fig. 15, in which the various parts corresponding to similar parts in Fig. 9 are designated by the same respective reference numerals as the latter. The oscillator 80 is a tube of the screen grid type, the resistance contacts 81 and 82 being adjusted so that the tube is self-oscillating. The value of the inductance 83 in the plate circuit and the potential on the plate are made such that the tube is self-oscillating at some frequency below the required horizontal synchronizing frequency of 1200 cycles. The received synchronizing impulses taken from the resistor 39 by the contact 52 and applied to the grid of the tube through a suitable step-up transformer 84, drive the tube and maintain its frequency of oscillation at the frequency of these 20 impulses which, in this case, is 1200 cycles. As an alternative, it is proposed to adjust the plate potential and make the value of the inductance 83 such that the tube 80 is just below the point 25 of self-oscillation. The received synchronizing impulses then drive the tube as before, to maintain the same in oscillation at the frequency of these impulses. In either case, a current wave roughly approximating a saw-tooth, as shown in Fig. 16, is obtained in the inductor 83. This current wave has a very short return period t' , and causes a voltage wave of substantially the shape shown in Fig. 17 to develop across inductance 83. The amplitude of the peaks 85 of the voltage 30 wave is proportional to the slope of the return line of the current wave, and their period of duration is equal to the return period t' of the current wave. The return period t' is so short that voltage peaks of great magnitudes are generated, voltages as high as 5,000 volts being possible 35 with use of screen grid tubes of usual construction. From this it will be seen that the discharge tube 55a in Fig. 15 can be biased much farther below cutoff than is possible in Fig. 9, so that it requires a relatively higher positive 40 voltage to swing the grid, the value of this voltage being indicated by the dash line 86 in Fig. 17. Since only the tip portions 87 of the peaks 85 are effective to swing the grid, it will be seen that the discharge period of tube 55a in Fig. 15 is 45 only a fraction of the short return period t' . Tube 55a in Fig. 15, therefore, discharges condenser 56 only an infinitesimal period of time, so that a very favorable saw-tooth voltage wave 50 is obtained, the ratio of the charging period to the discharging period being considerably higher than is the case in the circuits in Figs. 8 and 9.

As shown, the voltage was across inductor 83 in Fig. 15 is applied to the grid of tube 55a by a coil 83a inductively coupled to coil 83. 60

Fig. 18 shows a proposed D. C. amplifier connection between the discharge tube 55a and the tube 61 in Figs. 9 and 15, whereby the condensers 59 and 60 and the resistor 88 are eliminated. In this connection, a self-biasing resistor 89 65 raises the potential on the cathode of tube 61 positive with respect to ground by an amount equal to the D. C. component of the voltage on condenser 56 plus the normal bias voltage for tube 61. The condenser 56 is made just large 70 enough so that the tube 55a discharges the same only enough to give the required swing on the grid of tube 61. By varying the charging resistor, as well as the capacity of condenser 56, this swing may be placed on the most advanta- 75

geous portion of the charging curve, whether linear or curvilinear.

The D. C. amplifier connection in Fig. 18 has been found to contribute toward more linear saw-tooth waves and, correspondingly, better scanning than has been obtained with the connection shown in Figs. 9 and 15 between tubes 55a and 61.

Fig. 21 shows the approximate voltage wave shape that is required across a circuit, comprising an inductor and resistor in series, to cause a saw-tooth current wave to pass through the same. The voltage wave 70 in Fig. 8 has this shape. In Fig. 21, the amplitudes of the parts A and B of the wave are determined by the length of return line of the saw-tooth current wave and by the ratio of inductance to resistance in the circuit, such as the coils 49 in Figs. 8, 9, and 15.

When the charging voltage supply for the condenser 56 is many times the voltage to which it charges before being discharged, the wave shape of the A. C. component of the voltage on the condenser is a linear saw-tooth, as shown in Fig. 19. Furthermore, the current wave in the plate circuit of the discharge tube, such as tube 55a in Figs. 9 and 15, is an impulse wave such as is shown in Fig. 20, the impulses occurring during the return line periods t_r of the voltage wave in Fig. 19.

From the foregoing it will be seen that if the current wave in Fig. 20 were a reversed voltage wave, and if such a voltage wave be added to the voltage wave in Fig. 19, the resulting voltage wave will have a shape very similar to that shown in Fig. 21, and which is required to pass a saw-tooth current wave through a circuit having the same frequency-impedance characteristic as the coils 49 in Figs. 8, 9, and 15. For the purpose of accomplishing this, the circuit shown in Fig. 22 is proposed. In this circuit a dynatron oscillator 90, corresponding to the oscillator 80 in Fig. 15, operates in the same manner as the latter to supply sharp voltage peaks for driving a discharge tube 91 which corresponds to and operates in the same manner as the discharge tube 55a in Fig. 15 to develop across a condenser 93 a saw-tooth voltage wave as shown in Fig. 19. An impulse current wave, as shown in Fig. 20, occurs in the plate circuit of tube 91, and by interposing a resistance 94 between condenser 93 and the plate of tube 91, a reversed impulse voltage wave is developed from this current wave and added to the saw-tooth voltage wave to obtain the required voltage wave in Fig. 21. This required voltage wave is applied to the grid of a voltage amplifier tube 95 corresponding to tube 65 in Fig. 15, and is amplified and applied to the deflecting coils 49 to cause the required saw-tooth current wave to pass through the latter.

The resistance 94 is adjusted to match any relation of inductance to resistance of the circuit, such as coils 49, through which the saw-tooth current wave is to be passed. This adjustment corresponds to that in Figs. 8, 9, and 15 by which the frequency-impedance characteristic of the circuit 62 is made substantially identical to such characteristic of coils 49.

The circuit in Fig. 22 has the advantage that no tube, such as the tube 61 in Figs. 8, 9, and 15, is required. A further advantage resides in the fact that no compensating inductor, such as the inductance 63 in Figs. 8, 9, and 15, is required. In these figures, the inductance 63, tuned with the capacity of the tube 61 interconnected with it, and its own distributed capacity, is detrimental

to the obtaining of good saw-tooth waves above a certain frequency range. As there is no such inductance in Fig. 22, there is no such frequency limitation in this circuit. Still another advantage of the circuit in Fig. 22 resides in the fact that the conditions of polarity are such as to "swing" the power amplifier tube 95 in a favorable direction so that more usable power can be obtained from this tube than would otherwise be possible.

Each of the circuits in Figs. 8, 9, 15, and 22 are particularly adapted for the horizontal deflection system 51 in Fig. 7.

Each of the deflecting circuits shown in Figs. 8, 9, 12, 13, 15, 18 and 22 is characterized by the fact that it is effective to cause a saw-tooth current wave, at a frequency of at least one thousand cycles, to pass through the high impedance electromagnetic windings 49 for horizontal deflection of the cathode ray. It is important to understand that for this purpose each of these circuits is effective to generate the required shape of voltage wave described, and that in dealing with high impedance electromagnetic windings for deflecting the ray at least one thousand times a second, the required shape of voltage wave is substantially different from the saw-tooth shape desired for the current wave. In other words, my improved circuits represent a satisfactory solution of the problem of causing a saw-tooth current wave at a relatively high frequency to pass through electromagnetic deflecting coils or windings of relatively high impedance. Each of these circuits embodies a relaxation oscillator circuit, including the respective tubes 55, 73, 73a, 80, 55a and 90.

A circuit proposed for the framing or vertical deflection system 53 is shown in Fig. 23. In this circuit, a condenser 96 is continuously charged through a high resistance 97 from a source of high positive potential. A grid glow tube 98 operates, under control of the relatively strong framing impulses received and taken from resistance 38 by contact 54, to discharge the condenser and develop a saw-tooth voltage wave across the same of the same frequency as the controlling impulses which, in this case, is 20 cycles. This voltage wave is applied to the grid of a current amplifier tube 99 to cause a saw-tooth current wave to pass through the deflecting coils 50 connected in the plate circuit of this tube.

The bias on the grid of the discharge tube 98 is such that the same is brought up to the breakdown point only by voltage impulses of an amplitude at least as great as is occasioned by the relatively strong framing impulses received. It will, therefore, be understood that the received horizontal synchronizing impulses, which control or drive the system 51 for horizontal deflection of the ray 48, are ineffective with respect to the system 53 for the vertical deflection.

It is proposed in some cases to substitute for the capacitive coupling shown between the discharge tube 98 and amplifier tube 99, the D. C. amplifier connection shown in Fig. 18.

While the various values of inductance, resistance, capacity, and potential appearing in Figs. 8, 9, 15, 22, and 23 have been found to be satisfactory for successful operation, it will be understood that the same have been given by way of example only, and that they are not critical in any strict sense of the word and can be varied over a substantial range.

The manner of operating the receiving station is as follows, assuming that the circuit in Fig. 22

is used for the horizontal deflection system 51, and the circuit in Fig. 23 is used for the vertical deflection system 53.

The resistance contact 43 is adjusted to vary 5 the picture signal intensity until some visual indication is obtained on the screen 47. The frequency of the dynatron 90 is then adjusted so that the picture locks in step, as denoted by the picture remaining in place horizontally. The 10 vertical saw-tooth frequency is then adjusted, by means of the charging resistor 91, until the picture remains in place vertically. For final adjustment of the synchronizing action, the horizontal and vertical synchronizing controls are 15 varied until the picture is steady.

Too weak a synchronizing signal is indicated by a tendency of the picture to be unsteady. This condition is corrected by adjusting the contacts 52 and 54. If the vertical synchronizing 20 signals are too strong, the picture will "fold-up" and tend to synchronize at some multiple of the proper synchronizing frequency; the contact 54 is then retarded until this condition is corrected.

If the horizontal synchronizing signals are too 25 strong, the picture will be ragged along the edges thereof; this is corrected by retarding the control contact 52.

When the picture is properly synchronized, and the intensity control contact 43 adjusted to the 30 desired point, it will be found that the three control contacts 43, 52, and 54 for the respective picture and synchronizing signals are not interrelated, but that each operates independently of any control effect which would occur upon operation of the others. The entire adjustment of 35 the system is, therefore, comparatively easy.

When the shape of the framing hole at the transmitting station is as shown in Fig. 5, the system 53 at the receiving station for vertical deflection of the ray is adjusted so that the same 40 is responsive to an impulse which has either a greater amplitude or a greater duration than the horizontal synchronizing impulses. When the construction in Fig. 6 is used, the adjustment of system 53 is such that the same is responsive 45 only to the received framing impulses of substantially greater duration than the other impulses.

The term "dynatron" or "dynatron oscillator" in the claims is used in the broad sense, and is 50 intended to embrace a suitable thermionic device adjusted to be self-oscillating at some suitable frequency, or such a device having its frequency-determining circuit tuned to a desired frequency and adjusted at or in proximity to the point of 55 self-oscillation, or at least close enough to such point so that received synchronizing signals are effective to cause the device to oscillate at the required frequency.

The terms "drive" or "swing" in the claims 60 refer to the condition where an impulse is applied to an electrode of a thermionic device to make the same conductive or, in other words, to cause the device to draw plate current.

The terms "current wave" and "voltage wave", 65 as used in the specification and claims refer, strictly speaking, to the shapes of the curves or graphs obtained when voltage and current values are plotted against time. The term "return period" of a voltage or current wave, as used in, 70 the specification, refers to the period of time during which the voltage or current decreases from the maximum to the minimum values. In Fig. 16, for example, the return period of the current wave is designated by t' , the value of 75 which is determined by the projection of the

return line of the graph on the time axis. The return line of the current graph is, for convenience in explaining the operating action, referred to as the return line of the current wave.

It is contemplated, in some cases, to deflect 5 the ray 48 by electrostatic means, in which case suitable deflecting plates would be substituted for the coils shown, and the developed saw-tooth voltage waves applied directly across these plates.

Furthermore, it is seen that various changes 10 can be made such as in the size, shape and arrangement of the parts, and in the values of inductance, resistance, capacity and supply voltages without departing from the spirit of the invention or the scope of the claims. 15

I claim as my invention:

1. In television transmission apparatus photoelectric means, a scanning disc having a plurality of apertures, one of said apertures being able to pass a greater amount of light flux therethrough 20 than the remaining apertures, a light source positioned so as to impress light onto the photoelectric means in accordance with the size of the aperture in the disc as it is rotated, and means for rotating said disc whereby the light supplied to the 25 photoelectric means by said light source causes the generation of a series of reoccurring impulses for synchronizing purposes and wherein some of said impulses have a greater amplitude than others. 30

2. In television transmission apparatus photoelectric means, a scanning disc having a plurality of apertures, at least one of said apertures being of the same width and a greater height than the remaining apertures, a light source mounted so as to supply light to said photoelectric means in accordance with the size of the apertures in said disc during rotation of the disc, and means for rotating said disc whereby there are generated by the photocell reoccurring impulses for synchronizing 40 purposes and wherein all of said pulses are of substantially the same duration and some of said impulses are of greater amplitude than the others. 45

3. In television transmission apparatus photoelectric means, a scanning disc having a plurality of apertures, one of said apertures being of greater width and greater height than the remaining apertures, a light source mounted so as to supply light to said photoelectric means in accordance 50 with the size of the apertures in said disc during rotation of the disc, and means for rotating said disc whereby there are generated by the photocell reoccurring impulses for synchronizing purposes and wherein some of said impulses are of greater 55 duration and greater amplitude than the others.

4. In a system for television wherein picture signals and synchronizing signals are required, means for developing the picture signals, means for developing differing sets of synchronizing signals, said differing sets of synchronizing signals having different amplitudes, a phase reversal means connected to one of said signal developers, and means for mixing said picture signals and said sets of synchronizing signals whereby the picture 60 signals and synchronizing signals are of opposing polarity, the synchronizing signals being of the same polarity, but different sets of synchronizing signals being of different amplitude. 65

5. In a system for television, a cathode ray 70 tube, electromagnetic means for deflecting the ray, a thermionic device having a grid, means for applying to said grid a saw-tooth voltage wave, an electrical circuit connected in the plate circuit of said device, and an amplifier tube having 75

- a grid, said electromagnetic means connected in the plate circuit of said tube, said electrical circuit having a frequency-impedance characteristic substantially opposite to such characteristic of said electromagnetic means.
6. In a television system, a cathode ray tube, electromagnetic means for deflecting the ray, a condenser, means for continuously applying to said condenser a uniform charging voltage, a thermionic tube biased below cut-off and operable to discharge said condenser, means for applying to the grid of said tube regularly reoccurring electrical impulses above the cut-off point, an electrical circuit connected in the plate circuit of said tube, and an amplifier tube driven by the back E. M. F. voltage across said electrical circuit, said electromagnetic means connected in the plate circuit of said amplifier tube, the frequency-impedance characteristic of said electrical circuit being substantially opposite to such characteristic of said electromagnetic means.
7. In a television system wherein picture and horizontal synchronizing and framing signals are required for operation of the receiving station, means forming part of the transmitting station for generating said three kinds of signals, the framing signals being substantially greater in intensity than the horizontal synchronizing and the peak-picture signals, the horizontal synchronizing signals being substantially greater in intensity than the peak-picture signals, radio receiver means forming part of the receiving station for intercepting the transmitted signals; first, second, and third resistances each connected independently of each other across the output side of said receiver means; picture-developing means supplied with picture signals from the first resistance, scanning apparatus supplied with horizontal synchronizing signals from the second resistance, and framing apparatus supplied with framing signals from the third resistance.
8. In a television system wherein a saw-tooth current wave is to be passed through electromagnetic ray deflecting means for the purpose of linearly deflecting said ray, means for linearly charging a condenser, a thermionic discharge tube connected to said condenser and forming a discharge path therefor, means for periodically rendering the thermionic tube conductive, and means for adding to the voltage wave across said condenser a voltage wave similar to the occurring current wave through the tube forming the discharge path for said condenser.
9. In a television system, electromagnetic means for effecting scanning action at the receiving station, a voltage amplifier tube, said electromagnetic means connected in the plate circuit of said tube, a condenser connected in the grid circuit of said tube, means for developing a saw-tooth voltage wave across said condenser, and capacitative means connected in one of said circuits of said tube for reshaping said voltage wave to a voltage wave shape effective to cause a saw-tooth current wave to pass through said electromagnetic means.
10. In a television system, an electron device provided with screen structure and with means for developing a beam of electrons directed at said structure, and means for deflecting said beam, said deflecting means including an electromagnetic winding and means for causing a substantially saw-tooth current wave at a frequency of at least one thousand cycles to pass through said winding; said last-named means including a relaxation oscillator circuit comprising a condenser-discharge tube provided with a grid, means supplying the grid of said tube with a negative biasing potential substantially greater than the negative potential for cut-off, and a dynatron oscillator supplying voltage peaks to the grid circuit of said tube wherein the tip portions only of said peaks are effective to cause said tube to draw current.
11. In a television receiving system, a cathode ray tube provided with a fluorescent screen and with means for developing a ray of electrons directed at said screen, means for deflecting said ray, said deflecting means including an electromagnetic winding and means for causing a substantially saw-tooth current wave at a frequency of at least one thousand cycles to pass through said winding; said last-named means including a relaxation oscillator circuit embodying a condenser-discharge tube provided with a grid, means supplying the grid of said tube with a negative biasing potential substantially greater than the negative potential for cut-off, and a thermionic tube supplying voltage peaks to the grid circuit of said condenser-discharge tube wherein the tip portions only of said peaks are effective to cause condenser-discharging action of said tube; and means for controlling operating action of said thermionic tube in accordance with received synchronizing electrical effects.
12. In a system of the character described, an electron device provided with means for developing a beam of electrons, and means for deflecting said beam; said deflecting means including an electromagnetic deflecting coil, and a relaxation oscillator circuit for developing a voltage wave form effective to cause a saw-tooth current wave to pass through said coil; said circuit comprising a thermionic condenser-discharge tube biased below the cut-off point and having a substantially non-inductive plate circuit, and a condenser and a resistance connected in series, the condenser-resistance series being connected across the plate circuit terminals of said tube.
13. In a system of the character described, an electron device provided with means for developing a beam of electrons, means including an electromagnetic coil for deflecting said beam, and means for causing a saw-tooth current wave at a frequency of at least one thousand cycles to pass through said coil, said last-named means embodying a relaxation oscillator circuit for developing a voltage wave at such frequency and of a form effective to cause said saw-tooth current wave to pass through said coil; said circuit comprising a thermionic condenser-discharge tube biased below the cut-off point and having a substantially non-inductive plate circuit, and a condenser and a resistance connected in series, the condenser-resistance series being connected across the plate circuit terminals of said tube.
14. In a system of the character described, an electron device provided with means for developing a beam of electrons, and means for deflecting said beam; said deflecting means including an electromagnetic deflecting coil and a circuit for causing a saw-tooth current wave to pass through said coil; said circuit including a network comprising a resistance and a condenser connected in series therewith, and a thermionic device for forcing a series of similar voltage impulses across said network to develop a saw-tooth voltage wave across said condenser and an impulse voltage wave across said resistance, said resistance provided with a tap whereby any desired amplitude

of the impulse voltages may be added to the saw-tooth voltage wave.

15. In a television system, an electron device, electromagnetic means associated with said device for deflecting the electrons, and means for causing a saw-tooth current wave to pass through said electromagnetic means; said last named means comprising an electrical circuit embodying an electron tube, and an electrical network connected in the output circuit of said tube and comprising a condenser and a resistance, said condenser and said resistance being connected in series relation to each other, said tube operating to develop across said network a voltage wave comprising a saw-tooth component appearing across said condenser and an impulse component appearing across said resistance.

16. In a deflecting circuit of the character described, an inductive circuit, and means for causing a saw-tooth current wave to pass through said circuit; said last-named means comprising an electrical circuit embodying an electron tube, and an electrical network connected in the output circuit of said tube and comprising a condenser and a resistance, said condenser and said resistance being connected in series relation to each other, said tube operating to develop across said network a voltage wave comprising a saw-tooth component appearing across said condenser and an impulse component appearing across said resistance.

17. In a deflecting circuit for deflecting a cathode ray beam, an inductive circuit for deflecting said beam, a condenser, means for linearly charging said condenser means for linearly discharging said condenser whereby said charging and discharging cause a saw-tooth voltage wave to be impressed across said condenser, a resistance connected in series with said condenser, means for impressing on said resistance a voltage impulse of a substantially saw-tooth shape, and means electrically connecting said inductive circuit to the condenser and resistance.

18. A system for deflecting electron passage in a cathode ray tube, comprising in combination a cathode ray tube provided with electron passage deflecting elements, saw tooth voltage generating means consisting of a condenser connected with a direct current source to be charged thereby at a constant rate and a vacuum valve having an anode, at least one grid and a cathode, said anode and cathode being connected to the terminals of said condenser respectively for short circuiting said condenser periodically, and means for generating periodical impulses from an independent oscillator which are supplied to said grid of said short circuiting valve to control the discharge of said short circuiting valve.

19. In a "sweep" circuit for the deflection plates of a cathode ray oscillosograph, a condenser included in said circuit, means for charging said condenser from a source of current at a constant rate, a vacuum tube having at least three elements therein, its plate-filament circuit being connected across said condenser, means for maintaining the grid of said tube highly negative while said con-

denser is being charged, and means for rapidly driving the grid positive long enough to discharge the condenser through the tube as and for the purpose described.

20. In a "sweep" circuit for the deflection plates 5 of a cathode ray oscillosograph, a condenser included in said circuit, means for charging said condenser from a source of unidirectional current at a constant rate, and means including, firstly a hard tube for discharging said condenser at a 10 high rate of speed, and secondly, an oscillator delivering a peaked voltage directly to the grid of said hard tube for the control thereof.

21. In a system for deflecting an electron beam in a cathode ray tube, a storage element and 15 means in combination therewith for charging and discharging said storage element at materially different rates of charge and discharge, an electron discharge device having a control electrode energized from said storage means, a thermionic 20 amplifier connected to the electron discharge device, an output circuit connected to the thermionic amplifier and a predistorting capacitative network connected between the electron discharge device and the thermionic amplifier. 25

22. In a television system wherein picture and horizontal synchronizing and vertical synchronizing signals are required for operation of the receiving station, means forming part of the transmitting station for generating said signals, one of 30 said synchronizing signals being generated substantially greater in intensity than the other of said synchronizing signals, receiver means forming part of the receiving station for intercepting the transmitted signals, and amplitude selection 35 means associated with said receiver means for separating the horizontal synchronizing signals from the framing synchronizing signals.

23. In a television system wherein picture and line synchronizing and framing signals are required 40 for operation of the receiving station, means forming part of the transmitting station for generating said signals, one of said synchronizing signals being generated substantially greater in intensity than the other of said synchronizing signals, receiver means forming part 45 of the receiving station for intercepting the transmitted signals, a channel selective to the amplitude of one of said synchronizing signals, and a second channel adapted to convey the other of 50 said synchronizing signals to a utilization circuit.

24. In a television system wherein video and line synchronizing and frame synchronizing signals are required for operation of the receiving station, means forming part of the transmitting 55 station for generating said signals, the frame synchronizing signal being generated substantially greater in intensity than the line synchronizing signal and the video signals, receiver means forming part of the receiving station for intercepting 60 the transmitted signals, a channel adapted to be actuated by the frame synchronizing signals, only, a second channel adapted to be energized by the line synchronizing signals, and a third channel adapted to be energized by the video signals. 65

ARTHUR W. VANCE.
